VACUUM TUBE

Alexander Senauke, New York, N. Y., assignor to
 Ampere X Electronic Products, Inc., Brooklyn,
 N. Y., a corporation of New York

Application October 14, 1936, Serial No. 105,475

4 Claims. (Cl. 250—27.5)

This invention relates to vacuum tubes, and more especially to vacuum tubes capable of operating at ultra-high frequencies, and of delivering relatively large amounts of power at such frequencies, without requiring expensive and cumbersome arrangements for water-cooling the tubes.

When tubes are desired to operate at ultra-high frequencies, such as above 20 megacycles, many obstacles are encountered to satisfactory operation, among the most important of which is the heating effect from dielectric losses, which becomes extremely important, and may in practice, determine the safe rating of the tube.

By designing the tube so as to reduce the various internal capacities of the tube it is possible to provide tubes which will operate at very high frequencies, but such tubes are characterized by very small electrodes, and are incapable of delivering any substantial power.

In accordance with my invention, I provide vacuum tubes which are so constructed that the internal electrodes may be made relatively large with consequent high heat dissipating capacity, and at the same time, the tube is capable of operating at ultra-high frequencies, contrary to present beliefs. By virtue of certain changes from the usual practice in design and production of the tubes, I have succeeded in eliminating many of the causes of excessive heating and resultant failure of tubes in such use, so that it is possible to satisfactorily utilize such tubes for commercial use at frequencies; and with power outputs, and under operating conditions heretofore believed impossible of attainment.

It is an object of this invention to provide a vacuum tube which will deliver substantially higher output power at higher frequencies than the tubes heretofore known, without requiring the use of forced cooling, such as by circulating water.

It is a further object of this invention to provide such a tube which is no more expensive to manufacture than the present types of tubes which are incapable of satisfactory operation under such conditions.

It is a further object of this invention to provide a tube capable of delivering relatively large power at ultra-high frequencies, and having inter-electrode capacities of an order heretofore believed too high to permit ultra-high frequency operation.

It is a further object of this invention to provide a tube of the class described which shall have a relatively long life when operating at

frequencies and under conditions where tubes of the usual construction quickly develop structural failure.

Still other objects and advantages of my invention will be apparent from the following specification.

The features of novelty which I believe to be characteristic of my invention are particularly pointed out in the appended claims. My invention itself, however, both as to its fundamental principles and as to its particular embodiments, is described in the specification and accompanying drawing, in which:

Fig. 1 is a front elevation, partly broken away, of a tube in accordance with my invention;

Fig. 2 is a detail side elevation of the anode end of the tube of Fig. 1, partly broken away;

Fig. 3 is a section on lines 3—3 of Fig. 1, and

Fig. 4 is a detail horizontal cross section on enlarged scale of the clamping collar.

In the design of vacuum tubes, two factors are of importance; first, the frequency at which the tube will deliver power, and second, the quantity of power which the tube will deliver in sustained operation without a rise in temperature sufficient to cause failure or material shortening of useful life.

These two factors are not independent. On the contrary, they are closely inter-related. For example, an attempt to use a tube in sustained operation at frequencies at which it will function for short periods may quickly develop so much heat as to cause structural failure, by collapse or puncturing of the glass envelope, or destruction of one or more of the interior elements, or otherwise.

I have discovered that certain beliefs heretofore considered as fundamental in tube design, are incorrect, and that certain factors heretofore regarded as immaterial, are of great importance in the design and construction of high frequency power tubes, and by applying my invention, I am able to produce tubes which may be identical with conventional prior art tubes as regards the heretofore normally considered characteristic determining essentials thereof, but which have greatly superior operating qualities, resulting from the embodying of features of my invention therein.

Comparing such prior art and improved tubes, they may have respectively filaments which are dimensionally and electrically identical, grids similarly identical, and plates identical in length and material, differing only in their inside diameter. Nevertheless, because of the incorpora-

tion of the features of my invention in such tubes, as will be more particularly described hereafter, they may be safely used under circuit conditions that would be practically instantaneously destructive to the prior art tubes, and at power outputs three to four times that of the prior art tubes. In addition, while the maximum frequency of such prior art tubes used at their full rating may be only 15 megacycles, the tubes 10 of my invention may be used at their full maximum rating (which is much higher than that of the prior art tubes) up to frequencies as high as 60 megacycles.

Referring now more particularly to Fig. 1 in 15 which I have illustrated a tube constructed in accordance with the principles of my invention, 1 designates the anode or plate, 2 the control electrode or grid, and 3 the cathode or filament.

In its preferred form the anode 1 is formed 20 of a hollow shell of graphite or carbon machined to the desired dimension and shape and provided on opposite sides with integral longitudinal fins or flanges 1^a, by means of which the plate may be secured in position in the plate supports 37 25 and 38 as by means of rivets passing through the channeled plate supports and through the fin or flange 1^a upon the plate.

The cathode, in this instance shows as a filament having a M convolution, is mounted at 30 its lower end upon leads 25 and 26 secured to heavy leads 22 and 23 which pass through the press 6 and are connected to base pins upon the base 50.

As will be understood, the base of the stem 5 35 is joined to the envelope 4 at the bottom and the base 50 is cemented thereto.

The upper bends of the filament may be held 40 resiliently in position by means of wire hooks 31 and 32 terminating in coil springs 33 and 34 resting upon and passing through insulator 36, which fits over and is secured to the upper end 45 of rods 9 and 10, around which the grid winding is wound and upon which it is carried. The convolutions of the grid winding preferably surround the filament.

The lower ends of rods 9 and 10 are secured, 50 as by welding, to a metallic ring or collar 8 which, in turn, surrounds a tubular extension 7 arising from the press 6. The upper end of the tubular extension 7 arising above the press is preferably left open and the upper edge of the collar 8 may be provided with a series of small fingers 8^a bent 55 inwardly over the edge of the glass tubing to prevent the collar slipping down out of position. The opposite ends 11 and 12 of the collar 8 may be bent outwardly to form projecting ears provided with openings 13 and 14 for receiving bolt 16 passing through the openings and which bolt 60 engages a nut 16^a by means of which the collar 65 may be clamped in position about the tubing. A shouldered insulating bushing 17 is preferably inserted between the head of the bolt and the collar 8 to insulate the two ends thereof from each other.

This insulation serves two purposes. First, it 65 permits higher degassing of the tube by induction heating of the anode, by interrupting the electrical continuity of the grid supporting collar 8. In the de-gassing operation in the bombarding machine, a high frequency current is induced in the conducting elements of the tube by placing outside the envelope a coil carrying high frequency current. If the collar were not insulated at its end, it would form a closed circuit and care would have to be taken during the 75

bombarding not to permit this collar to get too hot (by stopping or decreasing the heating at intervals). Such over-heating would result in cracking the glass or weakening it at the stem, permitting leakage and ultimate failure of the 5 tube. My construction permits the anode and other metallic parts of the tube to be heated continuously by high frequency bombardment to higher temperatures, thus permitting better degassing with less danger to the tube, and co-acting 10 with the other features herein described to provide a tube capable of operating at higher frequencies with higher power outputs. Secondly, the construction decreases the losses due 15 to absorption and dissipation of energy which would otherwise occur in the collar when the tube is operated at ultra-high frequency, because of the fact that, being interrupted by insulation the collar cannot operate as a closed circuit conductor in the high frequency field. 20

The anode, or plate, as previously stated, may be secured to the channel supports 37 and 38, which extend upwardly and inwardly and may be secured as by welding to a metal collar, or ring, 36, similar in construction to the collar 8 already described, the ring 36 surrounding stem 35 attached to the upper portion of the envelope 4. The ring 36 may be formed to provide ears 44 to be engaged by bolt 45 and a similar insulating bushing 17 may be interposed to prevent electrical 30 continuity in the ring 36. "Getter" cups 40 and 41 may be secured respectively to channel supports 37 and 38 by means of wires 42 and 43, the cups being open away from the grid and plate structure, as in Fig. 1 the cups being open 35 at the top. Prior to exhaustion of the tube, the getter material which is to be flashed may be placed within said cups. On flashing of the getter it will be deposited as a thin layer or film 46 upon the interior portion of the envelope and 40 stem above the getters cups.

The plate cap 51 may be cemented to the upper portion of the envelope 4 and is preferably made relatively large in size, extending downwardly to cover substantially the entire neck portion of the envelope, or if no neck is present to cover substantially all of the portion of the envelope where the getter is deposited, and connection to the plate or anode is made by means of a lead-wire 51^a passing through the upper press 55 at the lower extremity of stem 35 and connected to the supporting system for the plate. It will be seen that in operation the plate, the supports 37 and 38, the collar 36, the lead-wire passing to plate cap 51, and the plate cap itself are all 60 at the same potential. It will also be noted that the grid-filament assembly, on the one hand, and the plate assembly, on the other, are not mechanically connected by any bracing structure, 65 and are vacuum insulated from each other.

I have found that the positioning of the getter, as described, contributes substantially to the improved operating characteristics of the tube.

If the getter were deposited in its usual position on the side or bottom of the bulb, the getter deposit would act as a conductive plane which would increase the inter-electrode capacity of the tube by its mutual relation to the grid, plate and filament elements of the tube. In addition, there would also be established relatively intense electrical fields around the edges of the getter deposit adjacent the internal electrode of the tube, which would cause local heating by dielectric absorption of energy in the glass of the envelope. This local heating reduces the efficiency of the 75

tube and may cause bulb failure evidenced by local deflection or puncturing of the envelope in operation. These electrical fields may occur externally as well as internally of the tube.

5 Depositing the getter as explained with reference to Fig. 1, places the getter deposit 46 entirely or very substantially within the anode or plate cap, so that it is shielded by the said cap from outside electrical influences, and also places 10 it in a relatively weak electric field because the cap and the more massive internal elements, such as the plate supporting collar, the plate supporting channels and the plate itself, are all at the same electrical potential at all times 15 and consequently little or no dielectric field exists in the envelope at the edges of the getter deposit to produce local heating.

When the getter is in this position, the inter-electrode capacity of the tube is a minimum low, 20 because the getter deposit has a minimum mutual capacity to the anode, cathode and control electrode. If each of these elements have substantial capacity to a getter deposit, the inter-electrode capacity of the elements themselves 25 will be thereby increased.

Preferably, connection to the grid or control electrode is made through a side terminal or grid cap 20 through lead 18 passing through the envelope and connected at its outer end to the 30 grid cap and at its inner end through flexible leads 19 to one of the grid supporting rods 10. The conductor 19 may and preferably will be made up of a number of flat metallic ribbons secured together at their ends. Preferably the 35 grid cap 20 is mounted upon a stand-off insulator 21 positioned under the grid cap and between it and the envelope 4 and cemented to the envelope 4. This serves to prevent corona discharge from the edge of the grid cap along the envelope in the direction of the plate, because of 40 the intense electrical field between the grid and the plate, which would cause local heating of the bulb at the upper edge of the grid cap and thus result in possible bulb failure by sucking in or 45 puncturing.

In the design of a power tube for operation at high frequency, the separation between the grid and the filament on the one hand and the plate and the grid on the other is particularly important. In this connection it is important to 50 note that, despite earlier beliefs to the contrary, the plate resistance and mutual conductance per unit area does not depend upon the spacing of the grid to filament and plate to filament, but solely upon the grid to filament spacing.

The important feature in the design of such a tube is to relate the separation between the grid and filament, on the one hand, and the plate and grid on the other, so that the ratio of grid 55 to plate transconductance, or mutual conductance, to the inter-electrode capacity and particularly, to the most important grid to plate capacity, is a maximum.

In this connection, by way of example, it may be stated that in two tubes in which the grid and filament spacings are the same, but the plate to grid spacing three times as large in the one as in the other, and in which the construction is 5 otherwise the same in both tubes, at the same space current, the mutual conductance of a tube according to my invention and having the larger plate-grid spacing, is actually higher than that of the other tube with the lower plate-grid 10 spacing.

Any changes in the internal construction and arrangement of the tube which cause this ratio to depart from its maximum value will result in reduced efficiency and reduced frequency at 15 which the tube may be employed at its full rating.

While I have shown and described certain preferred embodiments of my invention, it will be understood that modification and changes may 20 be made without departing from the spirit and scope of my invention as will be clear to those skilled in the art.

I claim:

1. A power tube capable of operation at ultra- 25 high frequencies, comprising an evacuated envelope, cathode, anode, and control electrodes positioned within said envelope, a conducting anode cap positioned on the outside of said envelope, and a conducting getter deposit on the interior 30 of said envelope, said anode cap covering substantially all of the portion of the envelope where the getter is deposited.

2. A power tube capable of operation at ultra- 35 high frequencies, comprising an evacuated envelope, cathode, anode, and control electrodes positioned within said envelope, a conducting tubular anode cap positioned on the outside of said envelope, and a conducting getter deposit within said envelope and substantially entirely 40 within said anode cap.

3. A power tube capable of operation at ultra- 45 high frequencies, comprising an evacuated envelope, cathode, anode, and control electrodes positioned within said envelope, a conducting anode cap positioned on the outside of said envelope, and a conducting getter deposit on the interior of said envelope, said anode cap covering substantially all of the portion of the envelope where the getter is deposited, and the 50 ratio of control electrode-anode transconductance to control electrode-plate capacity being a maximum.

4. A power tube capable of operation at ultra- 55 high frequencies, comprising an evacuated envelope, cathode, anode, and control electrodes positioned within said envelope, a conducting tubular anode cap positioned on the outside of said envelope and a conducting getter deposit within said envelope and substantially entirely 60 within said anode cap and the ratio of control electrode-anode transconductance to control electrode-plate capacity being a maximum.

ALEXANDER SENAUKE.
